UNITED STATES PATENT OFFICE.

JOHANN B. V. FÜRSTENWÄRTHER, OF BROOKLYN, NEW YORK.

MEDICINE CUP AND STOPPER.

SPECIFICATION forming part of Letters Patent No. 377,483, dated February 7, 1883.

Application filed May 26, 1887. Serial No. 239,402. (Model.)

To all whom it may concern:

Be it known that I, JOHANN B. V. FÜRSTENWÄRTHER, of Brooklyn, Kings county, New York, have invented a new and Improved 5 Medicine Cup and Stopper, of which the following is a full, clear, and exact description.

This invention consists in a cup of the desired dimensions, combined with and secured to a cork or stopper in such manner that the 10 cork will be at right angles with the vertical axis of the cup.

Reference is to be had to the accompanying drawings, forming part of this specification, in which Figure 1 is a view of the upper part of 15 a bottle, partly in section, provided with my improved cup and stopper, the stopper being shown in section. Fig. 2 is a cross-section of a cup carrying a stopper in accordance with my invention, and Fig. 3 is a perspective view 20 of my combined corkscrew and cup.

A in the drawings represents a cup or other receptacle, which may be made of any desired material—such as metal, celluloid, rubber, &c.

The cup A has secured to its side, at right 25 angles to the vertical axis of the cup, as shown in the figures, a corkscrew, a, for use in withdrawing a cork, b, from a bottle, c. When the screw is placed at right angles to the cork, the person using it can, by inserting a finger 30 in the cavity of the cup, readily extract the cork, Fig. 1. If desired, the corkscrew a may be dispensed with, and the stopper b, of any suitable material, may be glued or in other suitable manner firmly attached to the cup A 35 at right angles to its vertical axis.

The cup A may be made capable of holding any desired quantity of liquid—for instance,

a tea-spoonful, two tea-spoonfuls, a table-spoonful, &c.—and may be marked with appropriate inscriptions showing the capacity of 40 the cup for use by druggists and physicians. It will obviously perform the two functions of assisting to extract the cork from the bottle and to measure the quantity of fluid or other material taken from the bottle. If provided 45 with the corkscrew a, it can be readily applied to any cork or stopper of any size, and the cork, if worn out or unfit for use, can be exchanged for another. On the other hand, the 50 cork or corkscrew, which is attached to the cup at right angles to its vertical axis, will serve as a convenient handle for the cup whenever the cup is used apart from the bottle. The cup may also be used as a cover for the 55 bottle by being inverted and placed over the mouth thereof.

Unless the corkscrew is at right angles to the cup the latter, when filled, would have to be emptied at once. By my invention the dose can be laid aside on a table until the patient has been adjusted to receive it. The 60 bottom of my cup serves as a base to rest it on, the corkscrew not being in the way.

Having now described my invention, what I claim is—

The cup A, combined with the corkscrew a, 65 which projects at right angles from the side of the cup, leaving the base of the cup to form a support for the same, substantially as herein shown and described.

JOHANN B. V. FÜRSTENWÄRTHER.
